LIQUID FUEL BURNER

James Fletcher, Akron, Ohio, assignor to The Babcock & Wilcox Company, Newark, N. J., a corporation of New Jersey

Application January 17, 1933, Serial No. 652,132

19 Claims. (Cl. 299—120)

My present invention relates to the construction and operation of liquid fuel burners, and particularly to liquid fuel burners of the mechanical-atomizing type adapted for use over a wide range of capacities without change of parts.

Liquid fuel burners of the type stated have been heretofore proposed in which a supply of liquid fuel from a common source is divided into two or more independent controllable streams discharging through a common whirling chamber and nozzle opening into a furnace. In such constructions the passages to the whirling chamber are usually divided into two or more separate groups connected to separate feeds of liquid fuel. In the intended mode of operation of such burners, the liquid fuel supply connections are so arranged and controlled that the groups of passages may be used either simultaneously or separately. It has also been proposed to make the several groups of passages of different maximum carrying capacities whereby separate operation of the groups will provide different rates of discharge from the burner. Burner constructions of this type have been found to be inherently disadvantageous in that the burner parts surrounding the discharge passages not in use are continuously exposed to high furnace temperatures, causing solid deposits from the liquid fuel therein and consequently rapid clogging of these passages. Variable capacity liquid fuel burners heretofore in use in which the fuel flow is through the same discharge passages into a common whirling chamber at all loads have the inherent disadvantage that the angle and fineness of spray will vary substantially over their range of operation, due to the consequent changes in the rotational and axial velocity components of the fuel particles discharged.

The general object of my invention is the provision of a variable capacity mechanical-atomizing liquid fuel burner capable of effecting complete atomization of the fuel and maintaining its effectiveness over a wide capacity range. A more specific object is the provision of a mechanically-atomizing liquid fuel burner capable of delivering a fuel spray within the desirable ranges of spray angle and fineness over a wide capacity range. A further object is the provision of a liquid fuel sprayer plate having an improved construction and arrangement of primary and secondary liquid fuel discharge passages. A further object is the provision of a liquid fuel burner nozzle in conjunction with a sprayer plate of the character stated and having a whirling chamber and orifice constructed and arranged to provide efficient atomization over a wide fuel range with a

minimum pressure drop through the whirling chamber. A further object is the provision of fuel supply control means arranged to prevent operation of the burner other than in the most desirable manner.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of a liquid fuel burner constructed in accordance with my invention, the burner supporting means and combustion air supply and control means being omitted for purposes of clarity;

Fig. 2 is a sectional view on an enlarged scale of the nozzle shown in Fig. 1;

Fig. 3 is an end view on an enlarged scale of the sprayer plate shown in Fig. 1;

Fig. 4 is a section on the line 4—4 of Fig. 3;

Fig. 5 is a somewhat diagrammatic view illustrating the arrangement of the liquid fuel supply connections and supply control provisions; and

Fig. 6 is a somewhat diagrammatic view of the liquid fuel burner in an operating position.

The liquid fuel burner unit illustrated comprises a tubular outer casing or distance piece 10 adapted to be slidably mounted in operative relationship to an opening 7 through a furnace wall 8, as shown in Fig. 6. The inner end of the casing is threaded, as indicated at 11, for engagement with a suitable impeller 9 for directing a flow of combustion-supporting air around the discharge end of the burner, the impeller being advantageously constructed and arranged and the burner mounted substantially as shown in U. S. Patent No. 1,602,180 of T. B. Stillman, granted Oct. 5, 1926.

The fuel conduit and spraying parts of the burner are slidably mounted in the casing 10, and comprises a barrel 12 extending axially within the casing 10 and spaced therefrom by one or more centering spacers 13. At the outer end of the casing 10, the barrel 12 is threaded into a body member 15 having a passage 16 therein connected to a source of liquid fuel as hereinafter described. Within and extending axially beyond the ends of the barrel 12 is a pipe 17 having its outer end extending across the passage 16 and

opening into a separate passage 18 in the body member which is preferably connected to the same source of liquid fuel, as hereinafter described. Where operating conditions make it desirable, separate sources of the same fuel, or of different fuels may be used. The inner or discharge end of the burner is formed by a spray discharge head including a sprayer head 28 having its inner portion closely fitting around the inner end portion of the pipe 17 and an outer portion abutting and threaded on the inner end of the barrel 12. The inner end of the sprayer head has an annular recess 21 connected to the annular liquid fuel passage surrounding the pipe 17 by a series of parallel passages 22 symmetrically arranged about the axis of the sprayer head.

The supply of liquid fuel passing through the annular passage between the pipe 17 and barrel 12 is hereinafter designated the "primary" fuel supply, while the supply passing directly through the pipe 17 is hereinafter designated the "secondary" fuel supply.

The discharge head also includes a sprayer plate 25 connected with the recess 21 of the sprayer head by an outer series of symmetrically arranged ports or passages 27 extending parallel to the axis of the sprayer plate and preferably registering with corresponding ports 22. The central portion of the inner face of the sprayer plate is counterbored to form a circular whirling chamber 28, to which the primary fuel supply is delivered through a series of discharge nozzle-forming slots 30, preferably of rectangular cross-section, connecting corresponding ports 27 to the whirling chamber. The slots 30 are symmetrically arranged in a transverse plane normal to the axis of the whirling chamber and substantially tangentially to the whirling chamber, the outer walls of each slot being directly tangential to the chamber circumference. The number and effective cross-sectional area of the fuel passages and slots 30 used will vary with the desired fuel capacity range of the burner. With all such arrangements, a plurality of liquid fuel streams will enter the whirling chamber at circumferentially spaced points at a relatively high velocity and rotate about the periphery thereof in the same direction.

The sprayer plate is also formed with an inner series of ports or passages 29 symmetrically spaced about and extending parallel to the axis of the plate and connecting the secondary fuel supply pipe 17 to the whirling chamber. The secondary fuel ports 29 advantageously correspond in number to the primary fuel ports 27 and have their inner ends opening to the corresponding discharge slots 30 at points intermediate the length thereof, as shown in Figs. 1, 3 and 4. The cross-sectional area of the portion of the discharge slots between the secondary fuel ports and the whirling chamber is substantially increased in width and depth to permit greater fuel flows therethrough when both the primary and secondary ports are in use, without causing any substantial change in the rotational velocity of the primary fuel streams discharging into the whirling chamber.

The discharge head also includes a nozzle member 32 of substantially the same diameter as the sprayer head 28 and having a plane outer surface abutting the inner side of the sprayer plate and thus defining the inner side of the nozzle-forming slots 30. By this formation the machining operations required to form the slots are entirely confined to the sprayer plate. The nozzle

is formed with an axial discharge passage 33, formed as hereinafter described. The design of the nozzle passage 33, illustrated in Figs. 1 and 2, is the result of extensive study and experimentation with various forms of nozzle passages when associated with a sprayer plate of the character described. I have found that the quality and form of the spray discharged and consequently the flame conditions in the furnace are largely dependent upon the form of the nozzle passage. For example, if the periphery of the nozzle passage throughout its length is in alignment with the periphery of the whirling chamber, the whirling effect obtained will cause only partial atomization of the liquid fuel. Such a nozzle passage produces substantially a flat sheet spray, the spray having a number of heavy lines therein corresponding to the number of slots used, indicating that a large portion of the fuel is not atomized. I have found that the character of the spray is substantially improved by forming the nozzle passage with a restricted orifice 34 of a predetermined area, whereby the several streams approaching the orifice will be intimately mixed before their discharge into the furnace.

The specific form of the portion 35 of the nozzle passage forming a continuation of the whirling chamber was also found important. With a concave section preceding the orifice, the angle of spray was found to vary substantially with different rates of fuel discharge. Conditions are substantially improved by the use of a uniformly converging wall formation of the whirling chamber section 35 from its inlet to the orifice, as indicated in Fig. 2. Tests show that the angle of spray increases with increases in the included angle A of the whirling chamber section 35, and that the fuel capacity decreases with increases in the included angle of the nozzle, and vice versa, although the differences in capacity range for included angles of from 45° to 90° is not substantial. I have found that the most desirable value for the angle A to be 60°, that value giving the least overall pressure drop in the nozzle with both satisfactory atomization and at the most satisfactory angle of spray with reference to the air stream.

The portion 36 of the nozzle at the inner end of the orifice is also of conical form uniformly increasing in diameter and having an included angle B of sufficient size to avoid any dragging effect on the outer strata of the spray which would tend to unite the liquid particles in the outer strata. A set of such nozzle plates, each having the same degree of variation in capacity but with different orifice areas to provide different desirable maximum and minimum capacities, may be supplied to each user. The manufacture and interchangeability of the plate set is facilitated when all of the plates are of the same external size and shape. This is effected while maintaining the included angle A and maximum diameter of the section 35 constant, by making the angle B approximately 120°. With this construction, while the size and position of the orifice will change, no change in plate thickness will result.

The circumferential inner end portion of the nozzle 32 is cut away to form a seat for a cap member 38 which fits around the nozzle and sprayer plate and holds them in their intended positions relative to the sprayer head 28. The outer end of the cap 38 is internally threaded at 39 for engagement with the externally threaded inner portion of the sprayer head.

To permit periodic inspection and/or cleaning of the fuel burner, the burner parts positioned within the casing 10 are advantageously retractable without disturbing the position of the latter. For this purpose, the primary and secondary fuel supply connections to the body member 15 are advantageously flexible and readily detachable therefrom. As shown in Figs. 1 and 5, the outer end of the casing 10 is externally threaded for engagement by an adjustable collar 40 having pairs of wings 41 on opposite sides thereof carrying pivot pins 42 for upper and lower clamp arms 43 and 44, respectively. The portions of the body member 15 at the outer ends of the passages 16 and 18 are beveled as indicated in Fig. 1 to receive the rounded ends of ball joint nipples 45 carried in the clamp arms 43 and 44. The nipples 45 are threaded at their other ends to provide a valved connection to flexible primary and secondary liquid fuel supply lines 46 and 47, respectively. The free end of the clamp arm 44 carries a pivot pin 48 on which a clamp bolt 49 is mounted. The upper end of the clamp bolt is adapted to be received in the forked free end of the clamp arm 43 and is ordinarily held in that position by a washer 50 and clamp nut 51.

With the supply connections in their operating position, as shown in Fig. 1, inspection and/or cleaning of the burner parts is easily effected, after the supplies of liquid fuel have been cut off by closing cut-off valves 53 of any suitable type in the supply lines, by loosening the clamp nut 51 and swinging the clamp bolt out of engagement with the clamp arm 43. The clamp arms 43 and 44 may then be swung out of position carrying therewith the nipples 45. The burner parts within the casing 10 may then be retracted without disturbing the position of the latter.

With a liquid fuel burner constructed as described, changes in fuel capacity from minimum to maximum ratings with a given sprayer plate and nozzle while maintaining the spray angle and fineness within desirable limits are preferably secured by first operating with primary fuel alone at a pressure sufficient to secure satisfactory atomization. The capacity may be increased to a predetermined amount by increases in the primary fuel pressure. Further capacity increases are then secured by opening the secondary fuel supply line and supplying secondary fuel at the minimum secondary pressure effective to overcome the back pressure existing in the whirling chamber. Further increases in capacity are obtained by progressively increasing the effective secondary pressure to its maximum value. To change the burner capacity from maximum to minimum rating, the procedure is the reverse. I have found that a four-to-one capacity range with a spray of a desirable character is easily obtained in operation with a burner constructed as described.

In Fig. 5 is shown a liquid fuel supply system and control provisions arranged to insure the use of my preferred mode of operation. The liquid fuel is delivered under a high pressure from a common source to a supply main 55 connected to the primary and secondary branch supply lines 46 and 47, respectively. Control valves 56 and 57 are arranged in the supply main 55 and secondary supply line 47, respectively, and may be manually or automatically operated. The absence of any control valve in the primary supply line 46 insures a flow therethrough whenever

the burner is in use, and prevents the secondary being alone in operation. A further control effect may be had by varying the pressure of the fuel delivered to the main 55.

The particular sprayer plate formation described is especially advantageous in a wide range fuel burner of this type. When the primary supply alone is used the supply is substantially uniformly divided between all of the ports 27 and enters the whirling chamber substantially tangentially in several high velocity streams distributed about the circumference of the whirling chamber. The high rotational velocity of the streams in the whirling chamber is maintained throughout its length, the individual streams being gradually combined and united at the orifice, atomized by the centrifugal force acquired in the whirling chamber and enter the furnace in a hollow conical spray of substantially uniform fineness. The relatively wide exit angle of the nozzle passage permits an angle of spray at which an intimate mixture of the air and fuel streams will occur in the furnace with no retarding action on the outer spray strata. The finely atomized fuel particles in the spray are continuously scrubbed by the stream of air and desirable flame conditions maintained at all capacities. The described arrangement of the discharge slots and secondary fuel ports permits each stream of secondary fuel to enter the whirling chamber with no harmful influence on the corresponding stream of primary fuel. The secondary streams will mainly flow through the slots below and at one side of the primary streams, minimizing changes in velocity of the primary streams and thereby changes in the character of the spray developed. The primary and secondary streams from each slot enter the whirling chamber side-by-side. The arrangement of the discharge slots for the primary and secondary fuel feeds in a transverse plane normal to the whirling chamber axis greatly contributes to the maintenance of desirable spray conditions. Any fuel in the secondary ports when the primary ports alone are in operation is protected from the furnace heat by continuous passage of the primary streams across the ends of the secondary ports. Solid deposits from the liquid fuel in the secondary ports are thus minimized. A continuous cleaning of the portions of the discharge slots utilized by the secondary fuel will be effected when the primary feed alone is in use.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A mechanical-atomizing liquid fuel burner comprising a secondary liquid fuel supply conduit connected to a source of fuel supply, a discharge head at the discharge end of said conduit and including a substantially circular chamber, a series of secondary fuel ports connected to said fuel conduit and having their discharge ends arranged about the circumference of said chamber, a series of primary fuel ports arranged outside said secondary fuel ports, a separate liquid fuel supply conduit connected to a source of fuel sup-

ply and opening to said primary fuel ports, a series of nozzle-forming slots, each connecting a pair of corresponding primary and secondary fuel ports to said chamber, and a restricted outlet from said chamber.

2. A mechanical-atomizing liquid fuel burner comprising an axially arranged secondary liquid fuel supply conduit, a discharge head at the discharge end of said conduit and including a circular whirling chamber, a series of secondary fuel ports connected to said fuel conduit and having their discharge ends arranged outside the circumference of said whirling chamber, a series of primary fuel ports arranged outside said secondary fuel ports, a separate liquid fuel supply connection opening to said primary fuel ports, a series of nozzle-forming slots connecting said primary and secondary fuel ports to said whirling chamber, each of said slots extending substantially tangentially to said whirling chamber and having corresponding primary and secondary fuel ports opening thereto at spaced points along its length, and a restricted outlet from said whirling chamber.

25. 3. A mechanical-atomizing liquid fuel burner comprising an axially arranged secondary liquid fuel supply conduit, a discharge head at the discharge end of said conduit and including a circular whirling chamber, a series of secondary fuel ports connected to said fuel conduit and having their discharge ends symmetrically arranged outside the circumference of said whirling chamber, a series of primary fuel ports symmetrically arranged about said whirling chamber and outside said secondary fuel ports, a separate liquid fuel supply connection opening to said primary fuel ports, a series of symmetrically arranged nozzle-forming slots connecting said primary and secondary fuel ports to said whirling chamber and extending substantially tangentially to the circumference of said whirling chamber, the slot for each primary port registering with the discharge end of the slot of a corresponding secondary port, and a restricted outlet from said whirling chamber.

4. A mechanical-atomizing liquid fuel burner comprising a secondary liquid fuel supply conduit extending axially of said burner, a primary liquid fuel supply conduit surrounding said secondary fuel conduit, a sprayer plate at the discharge end of said conduits and having an outer series of ports opening into said primary fuel conduit, a central circular whirling chamber, an inner series of ports opening into said secondary fuel conduit, a series of nozzle-forming slots symmetrically arranged in a plane normal to the axis of said whirling chamber, each slot connecting corresponding inner and outer ports to said whirling chamber and extending substantially tangentially to said whirling chamber, and a nozzle contacting with the inner face of said sprayer plate and having a restricted axial discharge passage.

5. A mechanical-atomizing liquid fuel burner comprising a secondary liquid fuel supply conduit extending axially of said burner, a primary liquid fuel supply conduit surrounding said secondary fuel conduit, a sprayer plate at the discharge end of said conduits and having an outer series of ports opening into said primary fuel conduit, a central circular whirling chamber, an inner series of ports opening into said secondary fuel conduit and having their centers symmetrically spaced outside and relative to the circumference of said whirling chamber, a series of

nozzle-forming slots each connecting a pair of corresponding inner and outer ports to said whirling chamber and extending substantially tangentially to said whirling chamber, and a nozzle contacting with the inner face of said sprayer plate and having a portion forming a continuation of said whirling chamber progressively decreasing in cross-sectional area and an orifice at the reduced end of said whirling chamber.

6. A mechanical-atomizing liquid fuel burner comprising a discharge head having a whirling chamber, a series of discharge nozzle-forming slots extending substantially tangentially to said whirling chamber, primary liquid fuel supply connections to the outer ends of said slots, a secondary liquid fuel supply connection to said slots at points intermediate their length, a restricted outlet from said whirling chamber, a common source of liquid fuel, and control means arranged to provide a secondary liquid fuel supply from said common source only when said primary liquid fuel supply connection is open.

7. A mechanical-atomizing liquid fuel burner comprising a liquid fuel supply pipe, a second liquid fuel supply pipe concentric with said first named fuel pipe, means forming a fuel whirling chamber, a series of passages connecting one of said fuel pipes to said whirling chamber extending substantially tangentially to the circumference of said whirling chamber, passages separately connecting the other fuel pipe to said first named passages, and an outlet from said whirling chamber.

8. A mechanical-atomizing liquid fuel burner comprising a liquid fuel supply pipe, a second liquid fuel supply pipe within and concentric with said first named fuel pipe, means forming a fuel whirling chamber, a series of passages connecting said first named fuel pipe to said whirling chamber extending substantially tangentially to the circumference of said whirling chamber, passages separately connecting said second fuel pipe to said first named passages at points intermediate their length, and an outlet from said whirling chamber.

9. A mechanical-atomizing liquid fuel burner comprising a primary liquid fuel supply pipe, a secondary liquid fuel supply pipe within and concentric with said primary fuel pipe, a discharge head having a fuel whirling chamber, a series of nozzle-forming slots opening into said whirling chamber substantially tangential to the circumference thereof, passages connecting said primary fuel pipe to the outer ends of said slots, passages separately connecting said secondary fuel pipe to the same slots at points intermediate their length, and an outlet from said whirling chamber axially spaced from said nozzle-forming slot openings thereto.

10. A mechanical-atomizing liquid fuel burner comprising a primary liquid fuel supply pipe, a secondary liquid fuel supply pipe within and concentric with said primary fuel pipe, a discharge head having a fuel whirling chamber, a series of nozzle-forming slots symmetrically arranged in a plane normal to the axis of said whirling chamber and extending substantially tangentially to the circumference of said whirling chamber, passages connecting said primary fuel pipe to the outer ends of said slots, passages separately connecting said secondary fuel pipe to the same slots at points intermediate their length, and a restricted outlet from said whirling chamber axi-

ally spaced from said nozzle-forming slot openings thereto.

11. A wide range mechanical-atomizing liquid fuel burner comprising a discharge head having a substantially circular whirling chamber, a series of nozzle-forming slots having their inner ends discharging into said whirling chamber at an oblique angle to the circumference thereof, a liquid fuel supply connection opening to the outer end of each of said slots, and a separate liquid fuel supply connection opening to each of said slots at a point intermediate its length.

12. A wide range mechanical-atomizing liquid fuel burner comprising a discharge head having a substantially circular whirling chamber, a series of nozzle-forming slots having their inner ends opening substantially tangentially into said whirling chamber, a liquid fuel supply connection opening to the outer end of each of said slots, and a separate liquid fuel supply connection opening to each of said slots at a point intermediate its length.

13. A wide range mechanical-atomizing liquid fuel burner comprising a discharge head having a central substantially circular whirling chamber, a series of nozzle-forming slots having their inner ends opening substantially tangentially into said whirling chamber, a liquid fuel supply connection opening to the outer end of each of said slots, a separate liquid fuel supply connection opening to each of said slots at a point intermediate its length, and a restricted outlet from said whirling chamber.

14. A wide range mechanical-atomizing liquid fuel burner comprising a discharge head having a substantially circular whirling chamber, a series of nozzle-forming slots symmetrically arranged in a plane normal to the axis of said whirling chamber and having their inner ends opening substantially tangentially into said whirling chamber, a liquid fuel supply connection connected to the outer end of each of said slots, and a separate liquid fuel supply connection opening to each of said slots at a point intermediate its length.

15. A sprayer plate for a liquid fuel burner having a central circular whirling chamber formed in one face thereof, a nozzle-forming slot formed in said face and having its inner end opening substantially tangentially into said chamber, a liquid fuel supply passage connected to the outer end of said slot, and a separate liquid fuel supply passage opening through the

bottom of said slot at an intermediate point therein.

16. A sprayer plate for a liquid fuel burner having a central circular whirling chamber formed in one face thereof, a nozzle-forming slot formed in said face and having its inner end opening substantially tangentially into said chamber, a liquid fuel supply passage connected to the outer end of said slot, and a separate liquid fuel passage extending through said plate transversely of said face and opening through the bottom of said slot at an intermediate point therein.

17. A sprayer plate for a liquid fuel burner having a central substantially circular whirling chamber formed in one face thereof, a nozzle-forming slot formed in said face substantially tangentially to the circumference of said chamber and having its inner end opening to said chamber, an outer liquid fuel port extending through said plate and opening into the outer end of said slot, and a separate inner liquid fuel port extending through said plate and opening through the bottom of said slot at an intermediate point therein.

18. A sprayer plate for a liquid fuel burner having a central substantially circular whirling chamber formed in one face thereof, a series of nozzle-forming slots formed in said face substantially tangentially to the circumference of said chamber and having their inner ends opening to said chamber, a liquid fuel supply connection opening into the outer end of each of said slots, and a separate inner series of liquid fuel ports, each extending through said plate and opening through the bottom of one of said slots at an intermediate point therein.

19. A sprayer plate for a liquid fuel burner having a central substantially circular whirling chamber formed in one face thereof, a series of symmetrically arranged nozzle-forming slots formed in said face substantially tangentially to the circumference of said chamber and having their inner ends opening to said chamber, an outer series of symmetrically arranged liquid fuel ports, each extending through said plate and opening into the outer end of a corresponding slot, and a separate inner series of symmetrically arranged liquid fuel ports, each extending through said plate and opening through the bottom of one of said slots at an intermediate point therein.

JAMES FLETCHER.
